METHOD OF DYEING TEXTILE FABRICS

Application filed June 20, 1929 Serial No. 372,266.

My invention relates to methods of dyeing textile fabrics and has a particular reference to methods of producing multicolored designs on a printing surface and subsequently transferring these designs on a piece of textile fabric.

The object of my invention is to provide a method for producing artistic designs on printing beds by mechanical means and without the assistance of skilled artists.

For this purpose I prepare a printing bed by placing more or less large drops of a differently colored gelatinous like solution on a smooth surface of glass, metal, wood, etc. 15 Drops of different colors are arranged in accordance with the requirements of a design. These drops are then worked with a more or less blunt tool, such as a wooden stick, or a plurality of sticks arranged in a row, so 20 as to drag different colors in fancy streaks, thereby producing a definite pattern.

The design is then transferred on a piece of textile goods by a method similar to the one described in my copending application, 25 Serial No. 332,963 filed Jan. 16, 1929.

My invention is more fully described in the accompanying specification and drawings in which—

Fig. 1 is a view showing a printing bed 30 prepared by my method, Fig. 2 is the same printing bed in the preliminary stage of operation, Fig. 3 is a side view of a printing bed with the rake, Fig. 4 is a similar view in another projection, Figs. 5, 6 and 7 show different methods of raking the colors on the printing bed, and Figs. 8 and 9 show typical designs obtained by my method.

The printing bed is formed on a level surface of a piece of glass 1 or a similar material, impervious to water (such as marble, composition, impregnated wood, or wood covered with an oil cloth). The surface of the plate should be white in order to see the combinations of colors.

45 A colloidal gelatinous like solution is then prepared by dissolving in water such materials as Irish moss, gelatin etc., using excess of water in order to obtain a freely flowing thin solution. Where Irish moss is used the 50 gelatin-like solution preferably is made by

using one pound of moss and five gallons of water. This is boiled until the moss is thoroughly dissolved and then it is screened or filtered through a cloth and permitted to cool, when it forms into a freely flowing, 55 thin, jelly-like solution.

This solution is placed in several separate containers and in each container it is colored or dyed with suitable colors or dyes, preferably with aniline dyes, also with different 60 shades of the same color. A portion of the solution in one container is left undyed in its natural state. The dyes used preferably comprise aniline dyes of the common commercial type in which three ounces of the 65 dye may be dissolved in one gallon of water. After the dye is prepared in liquid form, varying amounts of this liquid are mixed with the gelatin-like solution, for example; eight parts of the gelatin-like solution may be mixed with one part of the dye liquid. If a lighter tone is desired, these proportions may be varied according to the 70 desires of the user.

Such differently colored solutions are then 75 poured in small portions 2 or placed in more or less large drops on the surface of the supporting plate 1 as shown in Fig. 2. The drops may be of different sizes and may be placed in a certain order or at random depending on the nature of the design. They 80 can be placed closely together to the extent of crowding each other in order to obtain a more or less uniform gelatinous like surface. No special accuracy is required in this 85 process, however, as with the subsequent working of the surface the solution becomes evenly spread over the plate, even if some distances were left between individual drops.

The solution must be of such density that 90 the drops will form a layer of about $\frac{1}{16}$ " thick.

The gelatinous layer is then worked with a rake comprising a row of more or less blunt pins 3 mounted on a bar 4. The character of 95 the design produced by my method depends to a large extent on the character of movement imparted to the rake. For instance, it can be moved in straight lines 5 (Fig. 2), first in one direction, then, displacing it side- 100

ways, for instance, by the width of one drop 2,—in another. Such transverse movement of the rake will cause the colors of different drops to merge into each other in sharp 5 pointed streaks, the effect produced being similar to the one shown in Fig. 1.

The design thereby obtained can be varied by changing the direction of raking, distance of side stepping between movements 10 in opposite directions, or by changing the path of travel. Instead of straight lines, the rake can be moved in curves, waves, spirals, figures 8 etc., some of the paths being illustrated in Figs. 5, 6 and 7. Combinations between 15 curves and curves and straight lines produce again different results.

The gelatinous like solution must be sufficiently thick to prevent the different colors from mixing together, so that when the pins 20 drag some of the solution of one color into the region of another, colored streaks are obtained, growing thinner as one color becomes gradually lost in another color.

Figs. 8 and 9 illustrate some of the designs obtained by my method. One of the important advantages of my method is that it provides a means for producing artistic and fancy designs by purely mechanical means and can be practiced by persons without any artistic training. The drops can be applied by some mechanical or, even, automatic devices, and similar automatic devices can be used for raking in any series of curves or lines.

35 The design is transferred from the printing bed onto a piece of textile fabric by a process as described in my copending application specified above. The cloth is applied to the printing bed, and when the design penetrates to the other side of the cloth, it may, if desired, be fixed in a 20% solution of alum, removed from the printing bed, washed, dried and pressed with hot iron.

I claim as my invention:

45 1. The method of dyeing textile fabrics comprising placing a plurality of drops of dye-carrying gelatinous-like solutions upon a supporting surface, each solution carrying a distinctive color dye, moving a mixing member through said drops to partially mix the same and produce a printing bed of predetermined types of color patterns, and laying a sheet of textile material on said printing bed to permit the dyes to enter said material.

55 2. The method of dyeing textile fabrics in fanciful patterns comprising placing on a supporting surface, a plurality of drops of gelatinous-like solutions to form a printing bed, each solution carrying a dye adapted to produce a distinctive color, drawing a blunt instrument through said drops in predetermined paths to cause said drops to come into fanciful patterns, permitting said drops to flow to a substantially level surface after 60 being comingled, and laying a sheet of tex-

tile fabric upon the printing bed and permitting the dye to soak into said fabric and transfer the patterns thereto.

3. The method of printing textile fabrics comprising forming a gelatine-like solution of water soluble dyes with Irish moss to provide dye-carrying gelatine-like solutions, placing a plurality of gobs of different dye color solutions on a supporting surface and permitting said gobs to flow into contact with each other, disturbing the natural figures formed by said gobs by drawing a blunt instrument through said gobs in a predetermined path to produce predetermined types of fanciful designs and form a printing bed, laying a sheet of textile material upon said printing bed and permitting said material to absorb the dyes to transfer the predetermined designs to said fabric.

4. The method of dyeing textile fabrics in predetermined types of fanciful designs comprising forming a printing bed of viscous dye carrying material flowed upon a support in predetermined zones of different dye colors, causing said viscous dye carrying material to come into predetermined types of fanciful patterns, and bringing a sheet of fabric into contact with said viscous material and permitting the dyes therein to soak into the fabric to transfer the patterns thereto.

5. The method of dyeing textile fabric in fanciful designs comprising forming a printing bed of viscous dye carrying material laid on a support in such manner as to provide adjacent zones of different colored dyes, causing the viscous material carrying different colored dyes to come into contact with predetermined types of patterns, and transferring said predetermined types of patterns to a sheet of fabric by laying the sheet of fabric on said dye carrying material and permitting the dye to enter the fabric.

Signed at Norwalk in the county of Fairfield and State of Connecticut this 16th day of May, A. D. 1929.

ALEXANDER J. BELOKOPYTOFF.
